MULTI-PANEL BLANK FORM ASSEMBLY
 John William Seekins, North Tewksbury, Mass., assignor to Courier-Citizen Company, Lowell, Mass., a corporation of Massachusetts
 Filed Apr. 9, 1962, Ser. No. 186,123
 7 Claims. (Cl. 282—12)

This invention relates to an improved blank form especially adapted for vehicle registration application forms.

In one type of vehicle registration application form, for example, the automobile form used in compulsory insurance States such as Massachusetts, the form includes a series of identical printed panels each of which must include the same basic information. After typing, the identical panels are separated along perforated lines with one copy for the State Registry of Motor Vehicles, one copy for the insurance company, one copy for the insurance agent, one copy for the automobile owner, etc.

It will be understood that the preparation of such forms usually occurs at the end of each year when several million automobile owners seek to register their vehicles and that time is of the essence in the handling of the same. Similarly, the problem of efficiently and rapidly typing an original and several copies of a registration certificate is encountered in other fields such as the registration of boats and outboard motors.

As far as I am aware, it is the usual custom for each typist, now filling in such forms, to use a separate sheet of carbon for each printed panel of the multiple application form, the carbons being small, difficult to handle and difficult to roll fold into a pack.

I use the term "roll fold" to distinguish from fan, or accordian, folding, the roll fold being around an end panel, as the centre of the roll, but the panels remaining substantially flat. It has been proposed to provide a book of small carbon sheets connected along the left side edge by a tab, the leaves of the book being placed individually and successively on each successive printed panel of the form as the form is slowly roll folded. Considerable manual dexterity is required on the part of the operator, to use such a carbon book without wrinkling of the sheets. In addition, the first printed panel of the typical application form includes the basic information which is to be copied on all panels, but also includes considerable additional information which is copied only once on a special copy sheet. Thus a book of small carbons makes no provision for the copying of the additional information and the operator must accomplish this separately or must add a long carbon to the roll folded pack, as an additional time consuming operation.

The principal object of this invention is to provide a blank form, of the type having a plurality of foldable printed panels, with a unitary, snap-out carbon, transfer assembly which underlies the panels and can be roll folded with the panels to form a pack ready for insertion into a typewriter.

Another object of the invention is to provide an automobile registration application form in combination with a transfer assembly which reproduces basic information typed on one panel, on all other panels, which reproduces additional information typed on that panel only on one other panel and from which the transfer sheets can be removed leaving the record sheets free of carbon ink, transfer areas.

A further object of the invention is to provide a multiple panel blank form and snap-out, carbon transfer assembly which is of low cost, easy to use and saving in time of a typist during a rush period.

Other objects and advantages of the invention will be apparent from the claims, the description of the drawing and from the drawing in which:

2

FIG. 1 is a front view of a blank form of the multiple panel type such as may be used for automobile registration applications.

FIG. 2 is a side view, in perspective, of the unitary, snap-out carbon transfer assembly of the invention, the transfer areas being cross hatched to distinguish them from other parts of the assembly.

FIG. 3 is a side view showing the transfer assembly underlying the multiple panel printed sheet of FIG. 1 and with the first roll fold shown in dotted lines.

FIG. 4 is a view similar to FIG. 3 but showing the roll fold completed to form a pack.

As shown in FIG. 1 a typical application sheet 20, of the automobile registration type, includes in the lower portion 21 thereof, the printed application blank 22, which is to be signed by the applicant, and the registration certificate 23 which will be authenticated and issued by the Registry of Motor Vehicles. The upper section of the blank 22 contains certain basic information such as the name, address, car model, etc. which must be duplicated for the use of the excise tax officials, the insurance company and the car owner, and this section has been designated as the first printed panel 24.

First printed panel 24 has been separated from the remainder of the application blank 22 by the full printed line 25 to delineate the extent of the panel and to separate it from the remaining printed portion 26 of blank 22 which calls for information as to garaging, source of title and the like. The upper portion 27 of the application sheet 20 includes a series of printed panels 30, 31 and 32, each identical with panel 24 and separated from each other by transverse lines of weakness 33, 34 and 35.

The second printed panel 30 and the fourth printed panel 32 are on the rear face 36 of sheet 20 and upside down, or inverted, while the first printed panel 24 and the third printed panel 31 are right side up on the front face 37 of sheet 20. An L-shaped figure has been illustrated on the panels, in place of the usual printing, the figure being shown right side up in full lines on panels 24 and 31 and upside down in dotted lines on panels 30 and 32.

To roll fold sheet 20 and superpose the panels into a pack, the panel 32 is folded on line 35 to underlie panel 31, then overfolded panels 31 and 32 are folded on line 34 so that they underlie panel 30 and then overfolded panels 30, 31 and 32 are folded on line 33 to underlie panel 24, thereby placing all panels in position to receive information typed on panel 24.

The unitary, snap-out carbon transfer assembly 40 is best shown in FIG. 2 and includes the main transfer sheet 41, the interleaf printed sheet 42 and the subsidiary transfer sheet 43, all three sheets being detachably secured to each other along the bottom edge by the common tab 44, the interleaf sheet 42 being separable along the perforated line of weakness 45.

The main transfer sheet 41, while elongated, is not as long as application sheet 20. The front face 47 of sheet 41 includes a transfer area 48, equal in dimensions to the dimensions of the second printed panel 30 on the rear face 36 of sheet 20, which it will underlie when the assembly 41 underlies sheet 20. The remaining portions 49 and 50 of the front face 47 of sheet 41 are free of transfer material, such as carbon ink, to avoid smudging of the portions of sheet 20 in engagement therewith. I call transfer area 48, the second transfer area because it transfers information onto the second printed panel 30.

The rear face 52 of main transfer sheet 41 is provided with transfer areas 53 and 54 which are longitudinally staggered with relation to area 48 and separated by an area 55 free of transfer material. I call transfer area 53 the fourth transfer area because it transfers information onto the inverted fourth printed panel 32 when the panel

32 is overfolded on line 35 as the first step in forming a superposed pack. I call the transfer area 54 the fifth transfer area because it transfers information onto a fifth printed panel to be described hereinafter.

The interleaved printed sheet 42 is equal in dimensions with the printed application blank 22 and includes the fifth printed panel 57 in the upper section of the front face 58 thereof for receiving the basic information of printed panel 24. Sheet 42 also includes the lower section 59 with the printed material of the lower section 26 of sheet 22 so that a separate transfer sheet, or carbon, is unnecessary to create a duplicate of the application blank 22. An L-shaped figure is shown on the additional, or fifth printed panel 57, which is right side up and identical with the L-shaped figures shown on panels 24 and 31, to illustrate the position of the printing thereon.

The subsidiary transfer sheet 43, is equal in dimensions with application blank 22, and interleaved printed sheet 42 and is provided with a transfer area 61 in the upper section of the rear face 62 thereof. I call transfer area 61, the third transfer area because it transfers information onto the third printed panel 31 when the form is roll folded into a superposed pack.

As shown in FIG. 3, in operation the application sheet 20 may be overlaid on the unitary transfer assembly 40 with the upper edge 65 in registration with the line of weakness 35, which brings the perforated line 45 of sheet 42 in registration with perforated line 64 of sheet 20 and brings the common tab 44 below the line 64 in a zone in which there is no blank space on panel 23 for typewritten information. The composite form is then roll folded on the lines of weakness 33, 34 and 35 of the sheet 20 and the corresponding transverse perforated lines 66 and 67 of the main transfer sheet 41, commencing with the overfolding of panel 32 on line 35. As shown in FIG. 4, the printed panels 30, 31, 32 and 57 and the corresponding panels of the main and subsidiary transfer sheets, are thus formed into a pack with a transfer area 48, 53, 54 and 61 overlying each printed panel whereby basic information typed on the first or outside panel, 24, is automatically reproduced on the other printed panels of the pack. While the composite form is still in the typewriter the typist can continue to type additional information on the section 26 of blank 22 which will be reproduced on the corresponding section 59 of interleaved sheet 42. The Registration certificate 23, contains printed material and blank spaces which differ from the material on panel 24 and, therefore, it is typed as the final operation on the application sheet 20, with no copies being required or desirable. The interleaved printed sheet 42 may be snapped out from between the transfer sheets 41 and 43 by grasping the upper edge 64 thereof with one hand and the tab 44 with the other hand and separating the sheet 42 on the perforated line 45. Thus the hands of the typist at no time contact the transfer areas, or carbonized ink areas, of the transfer sheets.

It should be noted that the record, or printed, application sheet 20, and the record, or printed, interleaved sheet 42, are entirely free of transfer material, such as carbon ink, so that there is no tendency toward smudging after these sheets are typed and in use. All of the transfer material, or carbon ink areas, are on the main transfer sheet 41, and on the subsidiary transfer sheet 43, which sheets may be discarded upon being detached or snapped out of the assembly, along perforated line 45, as explained above.

Another manner of using the device of the invention is to lay the sheet 20 on a flat surface, rear face up, fold panel 32 on line 35, lay the assembly 40 on sheet 20 front face up so that transfer area 53 is inserted under overfolded panel 32, fold panel 32 on itself twice and the set is ready for typing.

I claim:

1. A vehicle registration application form comprising

5 an elongated printed sheet free of transfer areas, said sheet having a first printed panel in the lower portion thereof and second, third and fourth printed panels in the upper portion thereof, said printed panels being joined by transverse lines of weakness and said second and fourth printed panels being inverted on the rear face of said sheet; and a unitary transfer assembly, said assembly including a main elongated transfer sheet underlying said first, second and third printed panels and having a second transfer area on the front face thereof in engagement with said inverted second printed panel and having first and third transfer areas on the rear face thereof opposite said first and third printed panels; an interleaved printed sheet free of transfer areas, said interleaved sheet having a fifth printed panel on the front face thereof underlying the first transfer area of said main transfer sheet, and a subsidiary transfer sheet underlying said interleaved printed sheet, said subsidiary transfer sheet having a fourth transfer area on the rear face thereof, said application form being roll foldable into a superposed pack for introduction into a typewriter with said second, third, fourth and fifth printed panels each overlaid by a transfer area of one of said transfer sheets for duplicating information typed on said first printed panel and said interleaved sheet being free of connection to said elongated printed sheet, but connected to said assembly along a perforated line whereby said interleaved sheet may be snapped out of said assembly without contact with said transfer areas.

30 2. In a blank form, the combination of an elongated printed sheet free of transfer areas, said sheet having at least four printed panels joined by transverse lines of weakness, said panels alternating on the front and rear faces of said sheet and being alternately right side up and upside down and a unitary transfer assembly, said assembly comprising a main, elongated, detachable transfer sheet having transfer areas alternating on the front and rear faces thereof; a printed interleaved sheet free of transfer areas, said interleaved sheet having an additional printed panel on the front face thereof; a subsidiary, short, detachable transfer sheet having an additional transfer area on the rear face thereof, and means on said assembly for removing said interleaved sheet without contact with the transfer areas on said transfer sheets, said transfer assembly being adapted, when said form is roll folded into a pack on said transverse lines, to reproduce information typed on the outside panel onto all of said other panels.

45 3. A blank form as specified in claim 2 wherein said main transfer sheet, said printed interleaved sheet and said subsidiary transfer sheet are secured to each other along one narrow edge to form a common tab and said interleaved is connected to said tab along a perforated line whereby said interleaved sheet and said transfer sheets can be snapped apart from each other.

50 4. In a blank form, the combination of an elongated, printed sheet free of transfer areas, said sheet having a series of printed panels joined by transverse lines of weakness, the panels on the rear face thereof being upside down and longitudinally staggered relative to the adjacent panels on the front face thereof whereby said panels are foldable into superposed pack form to produce an original and a plurality of copies in a typewriter; a unitary transfer assembly comprising a main detachable transfer sheet having a series of transfer areas, each equal in dimensions to one of said printed panels, said transfer areas being longitudinally staggered on the front and rear faces of said main transfer sheet; an interleaved sheet, free of connection to said printed sheet and free of transfer areas, said interleaved sheet having a printed panel on the front face thereof, similar to said series of panels; a subsidiary, detachable transfer sheet having a transfer area on the rear face thereof, identical in dimensions with said printed panels and means on said assembly for detaching said interleaved sheet therefrom without contact-

ing said transfer areas, said transfer assembly being operable to locate one said transfer area on each said printed panel, when said form is roll folded into a superposed pack for typing.

5. A combination as specified in claim 4 wherein said main transfer sheet includes lines of weakness between said transfer areas and the sheets of said transfer assembly are connected at one end only by a common tab, with said interleaf sheet separable from the remainder of said assembly, along a perforated line.

6. As an article of manufacture, a printed blank form free of transfer areas, said form having a series of identical, printed panels adapted to be folded into a pack for simultaneous reproduction in a typewriter and a unitary, transfer assembly adapted to be folded with said form to superpose a transfer area on each said printed panel, said assembly including a main transfer sheet with longitudinally staggered, transfer areas on each opposite face thereof, an interleaf sheet free of transfer areas, said interleaf sheet having an additional, identical, printed, panel thereon, a subsidiary transfer sheet having an additional, identical, transfer area on the rear face thereof and finger tab means on said transfer assembly for snapping out said interleaf sheet therefrom.

7. A unitary transfer assembly, for use with an elongated blank form of the roll foldable, multiple panel type, said assembly comprising a main, elongated, transfer sheet having a series of transfer areas alternately on the front and rear faces thereof, a subsidiary, short, transfer sheet having a single transfer area on the rear face thereof, said transfer sheets being adhered to each other along one edge to form a snap-out tab and an interleaf printed sheet free of transfer areas, said interleaf sheet secured along one end edge, by a perforated line connection to said tab and lying between said transfer sheets, said transfer areas being adapted to reproduce typed information from one panel of said blank form onto other panels thereof, and onto said interleaf sheet, when roll folded into a superposed pack therewith.
